(57) **CLAIM**

The ornamental design for a motorized cleansing brush, as shown and described.

DESCRIPTION

FIG. 1 is a perspective view of a motorized cleansing brush; FIG. 2 is another perspective view of the motorized cleansing brush of FIG. 1;

FIG. 3 is a top plan view of the motorized cleansing brush of FIG. 1;

FIG. 4 is a bottom plan view of the motorized cleansing brush of FIG. 1;

FIG. 5 is a right-side elevation view of the motorized cleansing brush of FIG. 1, the left-side elevation view being a mirror image of FIG. 5;

FIG. 6 is a front elevation view of the motorized cleansing brush of FIG. 1; and,

FIG. 7 is a back elevation view of the motorized cleansing brush of FIG. 1.

The broken lines are directed to unclaimed portions and form no part of the claimed design.
